ABSTRACT OF THE DISCLOSURE

A process for the reductive dimerization of α,β -unsaturated nitriles, amides or esters susceptible to Michael reaction by treatment with alkali metal or alkaline earth metal amalgams in the presence of compounds which are proton donors but do not react appreciably under the reaction conditions, particularly water, and in the presence of hexamethylethylenetetramine.

This invention relates to the reductive dimerization of α,β -olefinic nitriles, carboxylic amides and carboxylic esters, particularly of acrylonitrile.

It is known from a number of patent specifications, for example U.S. patent specification No. 3,193,574 and British patent specification No. 1,063,497, that α,β -olefinic compounds, which are susceptible to the reaction known as Michael reaction (cf. *Organic Reactions*, vol. X, pages 179—555), for example acrylonitrile, acrylamide or acrylic esters, can be dimerized by treatment with alkali metal or alkaline earth metal amalgams in the presence of proton donors. These methods are as a rule carried out in a neutral to weakly alkaline medium, for example in the pH range of from 7.0 to 9.5. Inert solvents may also be used. It is preferred to carry out the methods using basic catalysts such as quaternary ammonium salts, unsubstituted or N-substituted amides, lactams, sulphonides, sulphones, sulphonates or ureas. In these prior art methods good yields of dimeric compounds with reference to reacted α,β -olefinic compounds are obtained with relatively low conversion rates or only low space-time yields are achieved.

It is an object of the invention to provide a process for the reductive dimerization of α,β -olefinically unsaturated nitriles, carboxylic amides or carboxylic esters susceptible to Michael reaction in which process high conversion rates and high yields and space-time yields are achieved.

It is another object of the invention to provide a process for reductive dimerization in which easily accessible compounds are used as additives.

We have found that α,β -olefinic nitriles, amides or esters which are susceptible to Michael reaction can be reductively dimerized by treatment with alkali metal or alkaline earth metal amalgams in the presence of proton donors which do not react appreciably with the olefinic compound under the reaction conditions, particularly water, at a high rate of conversion, with good yields and good space-time yields by carrying out the reaction in the presence of hexamethylethylenetetramine.

Particularly suitable α,β -olefinic nitriles, amides or esters which are susceptible to the Michael reaction are acrylonitrile, acrylamide and acrylic esters of low molecular weight alcohols, for example those having one to four carbon atoms, and also alkyl derivatives of the said compounds, for example those having one to three carbon atoms in the alkyl radical such as methyl, ethyl, propyl or isopropyl derivatives. Examples of other suitable olefinically unsaturated compounds apart from those

already specified are for example crotononitrile, crotonamide, and the corresponding methacrylic derivatives, such as methacrylonitrile, methacrylamide or methacrylic esters.

The most important application of the process is in the reductive dimerization of acrylonitrile to adiponitrile.

Alkali metal amalgams such as sodium, potassium, lithium, rubidium or caesium amalgams are generally used, but the process may be carried out just as well with alkaline earth metal amalgams such as magnesium, calcium or barium amalgams. Easily accessible sodium amalgams is preferred.

The content of alkali metal or alkaline earth metal in the amalgam may vary within wide limits: it is preferred to use amalgams having a content of up to 0.8%, particularly from 0.01 to 0.4%, by weight of alkali metal or alkaline earth metal, it is however possible to use amalgams having a higher content than 0.8% by weight.

Water is particularly suitable for use as the proton donor. It is also possible however to use lower alcohols, alone or mixed with water, provided they do not react appreciably with acrylonitrile under the reaction conditions, for example lower alcohols having one to three carbon atoms such as methanol, ethanol or isopropanol.

The process is generally carried out by placing in a vessel the α,β -olefinic compound, the hexamethylethylenetetramine (which may also be prepared in situ from ammonia and formaldehyde) and the proton donor and then slowly adding the amalgam. Since reaction of the amalgam takes place very rapidly, large amounts of amalgam do not accumulate. The α,β -olefinic compound and the proton donor are as a rule used in the molar ratios which lie within the limits 5:1 to 1:6, particularly 2:1 to 1:3. Hexamethylethylenetetramine is advantageously used in an amount of from 0.05 to 1.2 moles, preferably from 0.1 to 0.5 mole, with reference to 1 mole of α,β -olefinic compound. The amalgam is usually supplied in an amount of from 0.01 to 0.8, preferably from 0.07 to 0.3, gram-equivalent of alkali metal or alkaline earth metal in the amalgam, with reference to 1 mole of α,β -olefinic compound.

It is advantageous to maintain a temperature of about 0° to 50° C. (for reasons of cooling preferably from 25° to 35° C.) in the reaction mixture. Furthermore it is advantageous to maintain a pH value of 7 to 10 in the reaction mixture, advantageously by adding polybasic acids, such as phosphoric acid, boric acid or sulphuric acid. It is also possible however to pass in hydrogen chloride or preferably carbon dioxide. It is advantageous to introduce carbon dioxide at a slightly superatmospheric pressure. When only the α,β -olefinic compound, hexamethylethylenetetramine and proton donors are used, the reaction mixture is often inhomogeneous. Provision therefore has to be made for good mixing to ensure thorough dispersion. It is also possible to provide for improved dispersion or for homogeneity of the solution however by adding inert solvents acting as promoters. Examples of suitable solvents are ethers which are miscible with water, such as dioxane or tetrahydrofuran, or polyhydric alcohols such as glycol or alkyl nitriles (cf. U.S. patent specification No. 3,356,708), sulphones or sulphonates (cf. French patent specification No. 1,467,091), or N-alkyl substituted alkane carboxylic acid amides such as dimethylformamide, N,N-dimethylacetamide or N-methylpyrrolidone (cf. the published papers of Dutch patent applications Nos. 6609103 and 6610715). Other additives which act as promoters, for example alkyl or aryl sulphonates or the corresponding free acids (cf. British patent specification No. 1,069,326) may also be used. The relative proportions used in the cited patent specification may be used. The content of α,β -olefinic compounds is generally more than 10% by weight with reference to the reaction mixture.

It is advantageous to add a conventional stabilizer for the α,β -olefinically unsaturated compound against undesired polymerization, for example hydroquinone or p-nitrosodimethylaniline. Amounts of from 0.1 to 1 p.p.m. with reference to the reaction mixture are generally used.

The reaction mixture may be worked up for example by separating mercury, filtering off any bicarbonate precipitated or dissolving it by adding water and then recovering the dimerization product. Since the process is preferably carried out in a two-phase system, it is sufficient to separate the organic phase and to fractionate it. The aqueous phase may be immediately reused. When the reaction has been carried out in the presence of a solvent in which a homogeneous phase forms, it is advantageous to extract the dimerized product with a non-polar organic solvent such as methylene chloride or toluene and then to separate the organic phase by distillation.

The invention is illustrated by the following examples. The parts are parts by weight unless otherwise stated.

EXAMPLE 1

5000 parts of sodium amalgam (with 0.28% by weight of sodium) is added within twenty minutes to 400 parts of a solution (consisting of 40% by weight of acrylonitrile, 20% by weight of hexamethylenetetramine, 20% by weight of water and 20% by weight of isopropanol) placed in a container provided with a thermometer, cooler, glass electrode for pH measurement, inlet pipe for carbon dioxide and a stirrer, while cooling with ice water and with vigorous mixing. The pH value in the reaction mixture is kept at 8.5 to 9.5 by passing in carbon dioxide and the temperature is regulated at 30° to 35° C. When all the amalgam has been added, the whole is stirred for a short time and then the mercury is separated, 800 parts of water is added to the solution and it is extracted once with 200 parts of toluene and then again with 150 parts of toluene. The organic phase is distilled. A yield of adiponitrile of 82% by weight with reference to acrylonitrile and a yield of 67% by weight with reference to amalgam is determined by gas chromatographic analysis.

EXAMPLE 2

The procedure of Example 1 is followed but an equivalent amount of sodium amalgam is used with 0.4% of sodium. The yield of adiponitrile is 86% of the theory

with reference to acrylonitrile and 60% with reference to sodium in the amalgam.

EXAMPLE 3

The procedure of Example 2 is followed but a mixture is used which consists of 40% by weight of acrylonitrile, 30% by weight of hexamethylenetetramine and 30% by weight of water. 3500 parts of sodium amalgam with 0.4% by weight of sodium is added to this emulsion within twenty-five minutes. The pH value is kept at from 8.5 to 9 by means of carbon dioxide and the temperature is kept at 35° C. When the reaction is over, mercury is separated and precipitated bicarbonate is filtered off and washed with a little water. The aqueous phase is separated from the organic phase and the latter is washed with a little water to remove hexamethylenetetramine and is then distilled. Adiponitrile is obtained in a yield of 84% with reference to acrylonitrile and of 65% with reference to amalgam.

We claim:

1. Improvement of the process for the reductive dimerization of acrylonitrile to form adiponitrile by treating it with alkali metal or alkaline earth metal amalgams at a temperature of from 0 to 50° C. and at a pH value of from 7 to 10 in the presence of a proton donor which does not react appreciably with the olefinic compound under the reaction conditions, which improvement comprises carrying out the reaction in the presence of from 0.05 to 1.2 moles of hexamethylenetetramine per mole of acrylonitrile.
2. A process as claimed in claim 1 in which the amalgam used is sodium amalgam.
3. A process as claimed in claim 1 in which the molar ratio of the acrylonitrile in the proton donor is from 5:1 to 1:6.
4. A process as claimed in claim 1 wherein the said amount is 0.1 to 0.5 mole per mole of acrylonitrile.
